UNITED STATES PATENT OFFICE.

THOMAS WRIGHT, OF JERSEY CITY, NEW JERSEY.

BODY-ELEVATING MECHANISM FOR VEHICLES.

1,157,487.

Specification of Letters Patent.

Patented Oct. 19, 1915.

Application filed December 27, 1913. Serial No. 809,026.

To all whom it may concern:

Be it known that I, THOMAS WRIGHT, a citizen of the United States, residing at Jersey City, in the county of Hudson and State of New Jersey, have invented a new and useful Body-Elevating Mechanism for Vehicles, of which the following is a specification.

This invention relates to mechanism whereby the body of a vehicle can be readily raised relative to the chassis, thus rendering the improvements particularly desirable for use in connection with coal wagons and the like.

Another object is to provide mechanism of this character which is simple in construction and compact.

A further object is to provide elevating mechanism which will hold the body against tilting laterally while lifted off of the chassis.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred forms of the invention have been shown.

In said drawings: Figure 1 is a side elevation of a portion of a vehicle having a body provided with one form of hoisting mechanism. Fig. 2 is an end elevation of the structure shown in Fig. 1. Fig. 3 is a section through one end of a cross strip. Fig. 4 is a side elevation of a portion of a vehicle and showing a modified form of hoisting mechanism. Fig. 5 is an end elevation of the structure shown in Fig. 4.

Referring to the figures by characters of reference 1 designates a portion of the chassis of a vehicle, the same having a suitable superstructure 2 thereon constituting a support or rest for the bottom frame 3 of the vehicle body 4, said body being of any preferred construction. Formed under the ends of the frame 3 are cross strips 5 and extending upwardly from the corners of the superstructure 2 are posts 6 preferably made of metal of the usual L or angle shape in

cross sectional contour. The corners of the frame 3 and of the cross strips 5 fit into the angle portions of these posts 6 so that the frame is thus held against lateral and longitudinal shifting relative to the chassis 1. Mounted within the upper end portions of the posts 6 are sheaves 7 and journaled upon the superstructure so as to extend longitudinally under the center of the frame 3, is a shaft 8, one end of which may be provided with a crank arm 9 or the like whereby the shaft may be rotated. Secured to this shaft is a drum 10 and secured to the drum are two hoisting chains, cables, or other flexible elements indicated at 11 and which diverge upwardly to the sheaves 7. It is of course to be understood that two drums 10 are employed, one being located near each end of the frame 3 so that there are thus two pairs of diverging hoisting elements 11, one pair extending from each drum. The hoisting elements of each pair extend over the sheaves engaged thereby and thence downwardly between the end posts 6 and through apertures formed within the cross strips 5, one of these apertures being indicated at 12 in Fig. 3. The flexible hoisting elements 11 are extended inwardly under the cross strips 5 from the openings 12 and are provided, at their inner ends, with bolts 13 extending into a turn buckle 14. Thus it will be seen that, by means of the turn buckles at the two ends of the structure, the flexible hoisting elements 11 can be drawn toward each other so as to be rendered taut while the frame 3 is resting on the superstructure 2 and, consequently, when the shaft 8 is rotated and all of the flexible hoisting elements 11 are wound upon the drums 10, the body and its frame 3 will be maintained horizontal at all times during the upward movement thereof, said body being guided in its movement by the angular corner posts 6. Top strips connect the upper ends of the posts 6 at each end, these strips being indicated at 15. These top strips 15 prevent the posts from spreading apart. The posts are also held together by means of crossed braces 16.

It is to be understood that any suitable means, such as pawl and ratchet mechanism as shown, may be provided for preventing the flexible hoisting elements from unwinding from the drums, while the body 4 is in elevated position.

It will be understood that the entire struc-

ture made up of the superstructure 2, the posts 6, the body and the operating mechanism, is complete in itself and is adapted to be applied to the chassis of a vehicle already constructed, it merely being necessary to secure the superstructure to the chassis in any suitable manner.

Instead of providing the hoisting mechanism shown in Figs. 1, 2 and 3, the modified construction shown in Figs. 4 and 5 can be utilized. By referring to these figures it will be seen that end posts 17 are mounted on a superstructure 18 adapted to be supported by the chassis of a motor vehicle or the like, these posts being connected at their upper ends by cross strips 18' on which are journaled short shafts 19 carrying sprockets 20. Journaled in suitable bearings 21 mounted on the superstructure 18 are longitudinal shafts 22, these shafts being parallel and each of them being provided with sprockets 23. Mounted on the sprockets 20 and 23 are endless chains 24 to the inner flights of which are secured brackets 25 fastened to the ends of cross beams 26. These cross beams are adapted to support the frame 27 on which the body 28 of the vehicle is supported. Each of the shafts 22 has an additional sprocket 29 secured thereto and these sprockets engage a crossed endless chain 30 so that, the two shafts will be caused to rotate in opposite directions. One of the shafts 22 is provided with any suitable means, such as a crank arm 30', whereby it can be rotated. From the foregoing it will be apparent that when the shafts 22 are actuated, the four lifting elements made up of the chains 24 will be simultaneously actuated, the chains at one side of the structure moving in a direction opposite to the other chains 24. Consequently the brackets 25 will be moved upwardly and downwardly in unison, thus maintaining the frame 27 and the bottom 28 horizontal during the elevation of the structure. It will be apparent of course that the chains 24 not only serve to lift the structure but also prevent lateral shifting of the frame 27 and body 28 relative to the posts 17.

What is claimed is:—

1. An attachment for the chassis of a vehicle, comprising a superstructure adapted to rest upon and to be secured to the chassis, of posts upstanding from said superstructure, a body supporting frame extending between the posts and normally resting upon said superstructure, a body upon said frame, a longitudinally extending shaft journaled upon the superstructure, revoluble elements supported by the posts and adjacent the sides of the two ends of the body, flexible hoisting elements mounted on said revoluble elements and connected to the two sides of each end of the body supporting frame, said shaft being extended beyond the ends of the body supporting frame and constituting means for simultaneously actuating the flexible hoisting elements to raise and lower the frame relative to the superstructure, all portions of the shaft and the parts mounted thereon being disposed above the bottom of the superstructure. 50 55 60 65 70

2. An attachment of the class described, including a superstructure adapted to rest upon and be secured to the chassis of a motor vehicle, posts upstanding from the corner portions of the superstructure, a longitudinal shaft journaled within the superstructure, revoluble elements supported by the posts, flexible elevating elements disposed in pairs, the elements of each pair being secured at one end to the shaft, means for adjustably connecting the elements of each pair at their other end, the said flexible elevating elements of each pair coöperating 85 to form a swing, a body supporting frame normally resting on the superstructure and extended at its ends into engagement with the respective swings, and means for rotating the shaft to raise or lower the body supporting frame relative to the superstructure. 75 80 90

In testimony that I claim the foregoing as my own, I have hereto affixed my signature in the presence of two witnesses.

THOMAS WRIGHT.
